United States Patent

Des. 235,295
Patented June 10, 1975

235,295

BOOK CART OR SIMILAR ARTICLE

Melville E. Junion, 104 Gregor Court,
Appleton, Wis. 54911

Filed Aug. 28, 1973, Ser. No. 392,274

Term of patent 14 years

Int. Cl. D6—04

U.S. Cl. D6—184

Fig. 1

Fig. 2

Fig. 3

FIG. 1 is a front right side perspective view of a book cart or similar article, embodying my new design;

FIG. 2 is a front elevational view thereof;

FIG. 3 is a top plan view thereof;

FIG. 4 is a front left side perspective view thereof;

FIG. 5 is a right side elevational view thereof; and

FIG. 6 is a back elevational view thereof.

I claim:

The ornamental design for a book cart or similar article, as shown.
